UNITED STATES PATENT OFFICE.

EMIL EDWARD RETTIG, OF SACRAMENTO, CALIFORNIA.

FILING DEVICE.

1,283,901.

Specification of Letters Patent.

Patented Nov. 5, 1918.

Application filed April 4, 1917. Serial No. 159,630.

To all whom it may concern:

Be it known that I, EMIL E. RETTIG, a citizen of the United States, and a resident of Sacramento, in the county of Sacramento and State of California, have invented a new and Improved Filing Device, of which the following is a full, clear, and exact description.

My invention relates to filing devices in the form of a spindle or rod on which letters, bills, accounts, cards or card systems, or indexes, or like articles may be placed.

The prime object of the invention is to provide a filing device of the indicated character in which relatively movable sections are arranged in a novel manner to permit ready access to and removal of any particular letter or the like without tearing.

The invention will be particularly explained in the specific description following.

Reference is to be had to the accompanying drawings forming a part of this specification in which similar reference characters indicate corresponding parts in all the views.

Figure 1 is a sectional side elevation of a filing device embodying my invention;

Fig. 2 is an enlarged vertical section of a portion of said device;

Fig. 3 is a side elevation given to illustrate one manner of dividing the filed letters, cards, or the like, into two general groups and separately supporting the same, whereby to make a removal or insertion of a particular filed article;

Fig. 4 is a sectional side elevation showing a slightly modified form of the lower end of a rod section;

Fig. 5 is a sectional side elevation illustrating another form of the invention;

Fig. 5^a is an enlarged vertical section of the upper portion of the device shown in Fig. 5;

Fig. 6 is a sectional side elevation of a filing device of the general form shown in Figs. 5 and 5^a, but somewhat modified;

Fig. 7 is a perspective view of the filing device in arched form;

Fig. 8 is a fragmentary view partly in section showing a portion of the filing device illustrated in Fig. 7.

Referring more particularly to Figs. 1, 2 and 3, the filing device is generally of spindle-like form, and includes a rod section 10 removably fitting within a hollow standard 11, the standard having a base 12 which may

alone be relied upon for base support, or it may be secured by screws 13 or the like to any suitable supplemental base or support 14. In any case the base support has a vertical hole in register with the hollow standard 11 through which the lower end of the rod section 10 extends to the under side of the base structure. In Fig. 1 a slot 15 extends laterally and downwardly in the rod section 10 to removably receive a retaining ring 16.

The rod section 10 extends above the tubular standard 11 and is shouldered to support a sleeve 17 into which the upper end of the rod section extends. A pointed terminal rod section 18 has telescoping connection with the upper end of the sleeve 17. A resilient connection is established between the rod sections 10 and 18 through the medium of an elastic band 19 which is detachably engaged with a slot 20 in the rod section 10 and with a similar slot 21 in the section 18. There is a separate sleeve section 24 between the shoulder produced by the reduced lower end of the terminal section 18 and the upper end of the sleeve 17, and a similar sleeve section 24^a at the lower end of sleeve 17.

The holding device in Figs. 1 and 2 is provided with means whereby the letters or other articles may be divided into two groups, said groups being adapted to be separately supported in either one of two ways that may be preferred, the construction permitting of either being utilized. Thus, a transverse pin hole 22 is formed in the rod section 10 in the reduced portion thereof, which is received within the lower end of the sleeve 17. A similar transverse pin hole 23 is formed in the reduced lower end of the terminal section 18. Referring to Fig. 3 it will be seen that the terminal section 18 has been withdrawn from the sleeve 17 and swung with the sleeve section 24 to a position at right angles to said sleeve 17, the elastic connection 19 serving to hold said terminal section in transverse position.

It will be seen that the slot is uppermost so that the elastic strand 19 will not become detached. Any particular number of letters, checks, cards or the like on the filing device may now be raised and passed onto the sleeve 17, after which the user will dispose the terminal section 18 and the rod section 10 at right angles to the sleeve 17 so that the letters, cards, etc., will be held on said

sleeve between the said rod section and terminal section, it being understood that the sleeve section 24 swings with the terminal section 18 and that the lower sleeve section 5 24^a will swing with the sleeve 17 or relatively swing by the swinging of the rod section 10 at right angles. The accidental displacement of the letters, etc., on the sleeve 17 having been thus guarded against, 10 the section 10 may be withdrawn from standard 11, and the upper letter or the like remaining on the standard may now be removed or another one placed on said standard and the rod section 10 replaced therein, 15 whereupon the sleeve 17 and the terminal section 18 may be restored to their original positions.

As an alternative means to group the letters or the like and sustain the upper group, 20 the section 18 may be slightly raised and a pin passed transversely through the upper pin hole 23. The tension of the elastic strand 19 will then exert pressure on the pin to prevent it from displacement and hold its 25 ends projecting beyond the sleeve. The sleeve 17 may be raised on the rod section 10 after the letters have been passed upward thereon and a second pin passed through the hole 22 to sustain the letters in 30 position. By using the pins it becomes unnecessary to swing the rod section 10 and the terminal 18 at right angles. The terminal section 18 is pointed for an obvious purpose and the transverse hole 25 is 35 formed therein near the point, through which a string may be inserted, so that the contents of standard 11 may be pulled up on the string for stringing and tying the same.

In Fig. 4 the parts are the same as described except that the rod section 10^a does 40 not extend through the base 14^a but terminates at the lower end of the standard 11.

In the form shown in Fig. 5 pins 26, 27 are employed and adapted to be passed 45 through transverse pin holes 28, 29 in the terminal section 18^a and in the rod section 10^b, which extends materially above the sleeve 11^a and directly receives the said terminal section, the latter being formed with 50 a tubular lower end 18^b receiving the reduced upper end 18^c of the section 10^b. To exert resilient pressure against the pins 26, 27 to prevent their accidental displacement, rubber blocks 30, 31 are employed, the block 55 30 being received in the tubular end 18^b of terminal 18^a. Steel balls 32 are employed with the blocks 30, 31 to take the wear and receive direct contact of the pins, whereby not to damage the rubber blocks. Also, a 60 steel ball 33 may be interposed between the block 30 and the reduced end 18^c of the rod section 10^b. The block 31 is received in a transverse slot 34 of the section 10^b and in order to afford access to the slot of the block 65 for renewal of the latter, a separate sleeve

section 35 is employed at the top of the standard 11^a so that only a small movement of the section 10^b is necessary to permit the renewal of the latter block.

The form shown in Fig. 6 employs a rod 70 10^c with practically the same elements and the same results characterizing the form shown in Fig. 5. The upper reduced end 18^f of said rod 10^c is inserted in sleeve 17^a to extend through said sleeve and through the 75 standard 11, that its slot 15 may receive a retaining ring 16. The string hole 25, pin holes 28^a, 29^a for pins 26, 27, are used as well as rubber blocks 30^a, 31^a, and metal balls 32^a in the transverse slots of the rod, similarly to 80 the construction shown in Fig. 5.

In the form shown in Figs. 7 and 8, an arched filing rod is provided, the construction including an oblong board or supporting block to which the bases 12^a of standards 11^b are suitably secured, said standards receiving the upright ends 10^d of the filing rod, said filing rod including a central removable section 18^g. The filing device in Figs. 7 and 8 is formed to receive pins 26^a, 27^a 90 for grouping the letters or the like on the standards 11^b and on the section 18^g. The pins when inserted are held against displacement by rubber blocks 31^a and balls 32^a, the blocks being received in slots 34^a in the 95 reduced ends 18^h of the section 18^g, which are received in the tubular ends 18ⁱ of the relatively fixed oppositely disposed terminals of standards 10^d.

The standards 11^b and the ends 10^d are 100 resilient to permit the same to be sprung apart sufficiently for the removal from either end 10^d of the intermediate section 18^g after withdrawing either pin 26^a or 27^a so that the said section 18^g and one rod section 10^d 105 may be swung laterally through an angle. The idea of swinging the section 18^g with one or other of the ends 10^d is to permit the removal, insertion, etc., of cards, letters, or the like. With this form of the invention, also, writing may be done upon either side of a card on the device without the removal of said card, that is to say, by withdrawing the pin 26^a, for example, all cards at the right thereof may now be passed laterally to 110 the left and downward on the sleeve 11^b, the particular card desired being thus at the top, to write upon that side of the card which is now uppermost. Or, if a particular card is to be written on the opposite side, the 115 cards may be passed onto the right hand sleeve 11^b of Fig. 7 by withdrawal of the pin 27^a, assuming the card desired was at the right of the pin 26^a.

I wish to state in conclusion that although 125 the illustrated examples constitute practical means for carrying out my invention, I do not limit myself strictly to the details herein illustrated since manifestly the same can be varied without departure from the spirit of 130

the invention as defined in the appended claims.

Having thus described my invention I claim as new, and desire to secure by Letters 5 Patent:

1. A filing device of the class described including relatively movable rod sections, one of which is formed with a transverse pin hole whereby to permit insertion of a pin 10 therethrough to bear against the adjacent member, and resilient pressure means acting to cause pressure against the pin.
2. A filing device of the class described, including a filing rod having transverse pin 15 holes therein, and spring-pressed means in the rod at the pin holes to exert yielding

pressure on the pins when inserted in the holes.

3. A filing device of the class described, including relatively movable rod sections, 20 means to support the same, and an elastic strand constituting a yielding connection between the rod sections.

4. A filing device of the class described, comprising tubular standards, means to support said standards, and an arched rod removably received at its ends in said standards and composed of relatively movable 25 sections, the said standards and the ends of the sections being resilient and tending to oppose relative movement of the sections.

EMIL EDWARD RETTIG.
